AUTOMATICALLY-LOCKING RESILIENTLY-BALANCED SASH GUIDE UNIT
Fred C. Osten, Sr., 14500 Abingdon Ave., Detroit, Mich.
Filed Dec. 4, 1961, Ser. No. 156,710
10 Claims. (Cl. 20—42)

This invention relates to tilttable and optionally removable sash windows and, in particular, to such windows equipped with automatically-locking spring sash balances when in the tilted positions of such windows.

One object of this invention is to provide a tilttable and optionally removable sash window which is pivotally mounted by pivot members threaded into the vertically-slidable elements of the sash balances and which threadedly engage these elements in such a manner as to lock these elements to the sash guides or sash balance casings in response to tilting of the sash out of the plane of the window frame for cleaning or other treatment in the tilted position of the sash or for outright removal thereof, whereby to hold the sliding elements in their attained positions and inactivate the sash balancing springs connected to them while maintaining these springs in their tensioned conditions.

Another object is to provide a tilttable and optionally removable sash window of the foregoing character wherein the pivot members have heads of non-circular cross-section engageable with notches in the sash frames to prevent relative rotation therebetween during such tilting of the sash and to cause the tilting of the sash to rotate the heads of the pivot members.

Another object is to provide a tilttable and optionally removable sash window of the foregoing character, wherein the pivot elements engage contact pads which in turn engage the sash guide or sash balance casing and thereby prevent nicking or denting thereof while distributing the contact over an extended area, so as to increase the frictional locking grip effected by the pads and prevent such nicking or denting.

Other objects and advantages of the invention will become apparent during the course of the following description of the accompanying drawings, wherein:

FIGURE 1 is a vertical section through a tilttable double-hung sash window installation in a plane perpendicular to the planes of the window panes, according to one form of the invention, with the midportion of the sash window installation omitted to conserve space and with the tilted position of one of the sashes shown in dotted lines;

FIGURE 2 is an enlarged fragmentary vertical longitudinal section taken along the line 2—2 in FIGURE 1, showing one of the sash balances in its unlocked position while the sash is in its vertical solid-line position of FIGURE 1;

FIGURE 3 is a view similar to FIGURE 2, but showing the sash balance of FIGURE 2 in its locked position with the sash in its tilted dotted line position of FIGURE 1;

FIGURE 4 is a fragmentary vertical cross-section taken along the line 4—4 in FIGURE 2;

FIGURE 5 is a vertical cross-section taken along the line 5—5 in FIGURE 2; and

FIGURE 6 is a fragmentary horizontal cross-section taken along the line 6—6 in FIGURE 2.

Referring to the drawing in detail, FIGURES 1 to 4 inclusive show a tilttable and optionally removable automatically-locking balanced sliding sash window installation, generally designated 10, according to one form of the invention as generally including a window frame 12 with opposite vertical side members 14 (only one of which is shown) carrying two resiliently-mounted spring-

2

balanced vertical sash guide units 16 (also one unit only being shown) yieldingly engaging lower and upper sliding sash units 18 and 20 respectively. Each of the lower and upper sash units 18 and 20 is provided with opposite side rails 22, a bottom rail 24 and a top rail 26, these rails collectively forming a sash frame, generally designated 28, containing a window pane 30 mounted in the open center thereof.

Each of the opposite vertical sash rails 22 is provided with a central rib 32 (FIGURES 3 and 6) having on its opposite sides flat lands 34 adapted to fit and slidably engage correspondingly-shaped channels 36 in each of two opposite sash guides 38 in opposite sash guide units 16. Each sash guide 38 includes two horizontally-spaced balancing spring housing or casing portions 40 (only one of which is shown in FIGURES 2, 3, 5 and 6). Each housing portion 40 contains one of two spring sash balance units, generally designated 42, these being located on opposite sides of the window frame 12. The housing portions 40 (FIGURE 6) are of approximately rectangular cross-section with opposite side walls 44, and front and rear walls 46 and 48, the front wall 46 being divided into two entrance flanges 50 by a vertical slot 52.

Mounted within each sash balancing spring housing portion 40 of each sash guide 38 is the elongated helical sash balancing tension spring 54 of each sash balance unit 42. The upper end of each spring 54 (not shown) is looped and thereby anchored to the sash guide 38 by being hooked over the upper end of the casing portion 40 thereof. The lower end of each sash balancing spring 54 terminates in a hook portion 56 (FIGURE 5) which is hooked through a horizontal hole 58 (FIGURES 2 and 3) in a rib 60 (FIGURE 5) at the top of a slide block or lock carrier 62. The slide block or lock carrier 62 is, as its name suggests, in the form of a vertically-elongated block of any suitable material, such as the polyamide plastic commercially known as nylon, and loosely but slidably fitting the housing portion 40 of each spring balance unit 42.

Each slide block of lock carrier 62 is bored and threaded as at 64 centrally and horizontally in line with the entrance slot 52 of its respective housing portion 40. The threaded bore 64 extends from the front surface 66 of the slide block 62 into a counterbore 68 of rectangular cross-section loosely and slidably receiving a pressure or contact pad 70 of soft steel, copper, brass or other suitable material adapted to provide frictional engagement with the rear wall 48 of the housing portion 40. Threaded through the bore 64 with its rearward end engaging the contact pad 70 is the shank 72 of a pivot screw 74 having a head 76 of non-circular cross-section, the head shape shown being of square cross-section.

Each sash 18 or 20 is pivotally supported between a pair of oppositely-facing pivot screws 74 which act as trunnions and are oppositely-threaded, like turnbuckle screws, to move outwardly in opposite directions and push their contact pads 70 in opposite directions against the rear walls 48 of their respective housing portions 40 in response to tilting of the sash 18 or 20 from its vertical position to its inclined position. Thus the pivot screw 74 shown in FIGURES 2 and 3 has a shank 72 with a left-hand threaded portion 73, whereas its opposite pivot screw (not shown) would have a right-hand thread on its shank. In actual practice, it has been found that a pair of oppositely-threaded $\frac{5}{16}$ —18 screws 74 is suitable for this purpose, the rotation thereof through the approximately 60-degree angle between the vertical and inclined positions of the sash 18 providing sufficient advance of the pivot screws 74 to bring about satisfactory locking engagement of the contact pads 70 with their respective rear walls 48 of their housing portions 40 on opposite sides of the window frame open-

ing occupied by the particular sash unit 18 or 20 under consideration. Each bottom rail 24 of each sash 18 or 20 is provided with a notch 80 of rectangular cross-section snugly but slidably fitting the square head 76 of its particular pivot screw 74 (FIGURES 2, 3 and 4). Either or both of the sash guides 38 is resiliently supported on compression springs 82.

In the operation of the invention, let it be assumed that the lower and upper sash units 18 and 20 are in their normal closed positions shown in FIGURE 1, with their panes 30 disposed in laterally-spaced parallel vertical positions. Let it also be assumed that the balancing springs 54 (only one of which is shown in FIGURE 1) are in their tensioned or stretched positions, resulting from the sash units 18 and 20 being in their closed positions, thereby counterbalancing the weight of the sashes 18 and 20. Let it finally be assumed that the user desires to tilt the lower sash unit 18 for cleaning its window pane 30 or for other purposes, and at the same time simultaneously lock the sash balance units 42 in their attained positions with their balancing springs 54 stretched or tensioned as shown in FIGURE 1.

To tilt the lower sash unit 18, for example, the user grasps its top rail or meeting rail 26 (not shown except for the upper sash 20) and swings it downwardly into the inclined position shown in the dotted lines in FIGURE 1. This action pushes either or both of the resiliently mounted sash guides 38 (depending upon whether only one of the sash guides 38 is resiliently mounted on one side of the window frame 12 or whether both sash guides are resiliently mounted). As the sash unit 18 swings from its vertical position to its inclined position (FIGURE 1), it pivots around the pivot screws or trunnions 74, the heads 76 of which engage the side walls of the notches 80 so as to be rotated in response to the tilting of the sash unit 18.

As the pivot screws 74 rotate in this manner, their shanks 72 move outward from their retracted positions of FIGURE 2 to their extended positions of FIGURE 3, pushing their respective contact pads 70 into tightly-locking frictional engagement with the rearward walls 48 of the housing portions 40. This action in turn pushes the front surface 56 of each slide block 62 tightly and frictionally against the front wall 46 of the housing portion 40. As a result, the slide blocks 62 are solidly locked to their respective housing portions 40 in their attained positions with their respective balancing springs 54 stretched or tensioned (FIGURE 1). The user may now wash or otherwise work on the window sash 18 in its tilted position and the lower end of the sash 18 will not fly upward because its sash balance units 42 have been locked immovably to their respective housing portions 40.

If, for instance, the window pane 30 is broken or for some other reason the user desires to remove the sash unit 18 as a whole from the window frame 12, he merely pulls upward and outward in an inclined direction parallel to the plane of the window pane 30, withdrawing the notches 80 in the lower sash rails 24 out of engagement with the heads 76 of the pivot screws 74, leaving the latter in their rotated and locking positions in the slide blocks 62. The user, after working upon the removed sash unit 18, replaces it by positioning it in the same inclined position in which he removed it (FIGURE 1), lining up the notches 80 in the bottom rail 24 with the heads 76 of the pivot screws 74 and then sliding the sash unit 18 downward in an inclined direction parallel to the window pane 30 until the screw heads 76 enter and reach the tops of the notches 80, as shown in FIGURES 2 and 4. In either event, whether merely tilting the window sash 18 for cleaning or other purposes or for removing it entirely, the operator after replacing it upon the pivot screws 74 in the manner described immediately below, swings the window sash 18 upward and inward into a vertical plane to its closed position shown in the solid lines of FIGURE 1.

In replacing the sash unit 18, the user wedges apart the sash guides 38, compressing their resilient mounting springs (not shown). When the sash unit 18 reaches its vertical position, however, the central ribs 32 of the opposite vertical sash rails 22 move into their respective channels 36 in the opposite sash guides 38 and at the same time rotate their respective pivot screws 74 and retract them from their projected locking positions of FIGURE 3 to their retracted or unlocking positions of FIGURE 2. In so doing, the pivot screws 74 relax their grip upon their respective contact pads 70, which disengage from contact with the rear walls 48 of the spring balance housing portions 40, whereupon the balancing springs 54 are unlocked and resume their balancing functions while permitting the lower sash 18 to be raised and lowered by sliding it upward or downward in its respective guide channels 36.

The removal of the upper sash 20 is similar to that described above for the lower sash 18, except that the relative positions of the various parts are reversed so that the meeting rail is pulled in order to tilt the sash 20, the upper rail 26 of which is notched and pivotally supported upon pivot screws similar to the pivot screws 74.

The pad 70 not only avoids or minimizes indentation of the rear wall 48 of the housing portion 40 but also increases the frictional engagement therewith. It will be evident, however, that the pad 70 may be omitted, whereupon the end of the pivotal locking screw 74 becomes the contact means which directly engages the wall 48 of the housing portion 40. Under such circumstances, locking still occurs but the inner end of the pivotal locking screw 74 is more likely to form indentations such as nicks or dents in the wall 48, particularly if the sash guide 38 is formed of aluminum or other relatively soft metal.

What I claim is:

1. An automatically-locking resiliently-balanced sash guide unit for tilttable sash windows, comprising an elongated sash guide including a hollow sash balance housing portion with vertical walls,

one of said walls having an elongated aperture extending longitudinally therealong and defining flange-like elongated vertical wall portions disposed on opposite sides of said aperture,

a resilient sash-balancing member mounted within said housing portion and having one end anchored thereto,

a lock carrier slidably mounted in said housing portion and connected to the opposite end portion of said sash balancing member,

said lock carrier having an approximately horizontal threaded bore therein aligned with said aperture,

a threaded pivotal locking member threadedly engaging said bore in rotatable relationship therewith for motion axially relatively thereto and,

said locking member having a coupling portion projecting outwardly through said aperture and adapted to engage said sash for rotation thereby in response to tilting of said sash,

and contact means connected to said locking member for motion relatively to said lock carrier into and out of locking engagement with another of said walls in response to rotation of said locking member.

2. An automatically-locking resiliently-balanced sash guide unit, according to claim 1, wherein said coupling portion has a head with flattened opposite sides adapted to engage the sash.

3. An automatically-locking resiliently-balanced sash guide unit, according to claim 1, wherein said coupling portion comprises a head of approximately rectangular cross-section on said locking member.

4. An automatically-locking resiliently-balanced sash guide unit, according to claim 1, wherein said lock carrier has a contact surface on the opposite side thereof from said contact means and adapted to be forced into engage-

ment with said flange-like wall portions in response to rotation of said locking member.

5. An automatically-tilt-locking resiliently-balanced guided sliding sash installation for mounting in a window frame opening, said installation comprising

a pair of vertically-disposed laterally-spaced elongated sash guides adapted to be mounted on opposite sides of the window frame,

a sash frame vertically slidably engaging said sash guides in tilttable relationship therewith and extending therebetween,

said sash frame near its lower corners having recesses therein

each sash guide including a hollow sash balance housing portion with vertical walls,

one of said walls having an elongated aperture extending longitudinally therealong and defining flange-like elongated vertical wall portions disposed in opposite sides of said aperture,

a resilient sash-balancing member mounted within each housing portion and having one end anchored thereto,

a lock carrier slidably mounted in each housing portion and connected to the opposite end portion of its respective sash balancing member,

each lock carrier having an approximately horizontal threaded bore therein aligned with said aperture,

a threaded pivotal locking member threadedly engaging each bore in rotatable relationship therewith,

one of said bores and its corresponding locking member having threads of opposite hand to the other bore and locking member,

each locking member having a coupling portion projecting outwardly through its respective aperture into coupled engagement with said sash for rotation thereby in response to tilting of said sash,

and contact means connected to each locking member for motion into and out of locking engagement with another of said walls of its respective housing portion for rotation by said sash in response to tilting of said sash.

5. An automatically-tilt-locking resiliently-balanced guided sliding sash installation, according to claim 5, wherein each of said coupling portions has a head with flattened opposite sides adapted to engage the sash.

6. An automatically-tilt-locking resiliently-balanced guided sliding sash installation, according to claim 5, wherein each of said lock carriers has a recess therein adjacent the inner end of said threaded bore, and wherein said contact means includes a locking pad mounted in 15 said recess for approximately horizontal motion relatively to said lock carrier.

7. An automatically-tilt-locking resiliently-balanced guided sliding sash installation, according to claim 5, wherein each of said lock carriers has a recess therein adjacent the inner end of said threaded bore, and wherein said contact means includes a locking pad mounted in 20 said recess for approximately horizontal motion relatively to said lock carrier.

8. An automatically-tilt-locking resiliently-balanced guided sliding sash installation, according to claim 5, wherein each of said coupling portions comprises a head of approximately rectangular cross-section on said locking member.

9. An automatically-tilt-locking resiliently-balanced guided sliding sash installation, according to claim 5, wherein each of said lock carriers has a contact surface

25 on the opposite side thereof from said contact means and

adapted to be forced into engagement with said flange-like

wall portions in response to rotation of said locking member.

10. An automatically-tilt-locking resiliently-balanced guided sliding sash installation, according to claim 5, wherein resilient mounting means is disposed in yieldingly-urged engagement with one of said sash guides.
